UNITED STATES PATENT OFFICE.

ARTHUR R. KEENE, OF HAVRE DE GRACE, MARYLAND, ASSIGNOR OF ONE-HALF TO JAMES LEE HOPKINS, OF HAVRE DE GRACE, MARYLAND.

NUT-LOCK.

No. 836,507.

Specification of Letters Patent.

Patented Nov. 20, 1906.

Application filed April 5, 1906. Serial No. 309,977.

To all whom it may concern:

Be it known that I, ARTHUR R. KEENE, a citizen of the United States, residing at Havre de Grace, in the county of Harford and State of Maryland, have invented certain new and useful Improvements in Nut-Locks, of which the following is a specification.

My invention relates to improvements in nut-locks, and has for one of its objects to provide a simple and inexpensive device of this character by means of which the nut when brought to a stop may be locked at such point without requiring it to be turned to any particular point.

Another object of the invention is to provide a construction that will enable the ready removal of the nut when desired.

The invention is illustrated in the accompanying drawings, in which—

Figure 1 is a vertical sectional view through a rail and the fish-plates at opposite sides thereof and shows a bolt and nut with my improved locking device. Fig. 2 is a side elevation of the same. Fig. 3 is an outer face view of the stationary locking-collar. Fig. 4 is an inner face view of the same. Fig. 5 illustrates in side elevation the three parts forming the locking device—to wit, the stationary collar, the locking-washer, and the nut; and Fig. 6 illustrates the inner side of the nut.

Referring to the drawings by numerals, 1 designates a rail to which in the present instance the bolt and nut-lock is to be applied, and 2 designates the fish-plates at opposite sides of the rail, which serve the usual and well-known function. The rail is provided with the usual bolt-hole 3, while the fish-plates are each provided with a hole 4 for the passage of the bolt, and one of the fish-plates has an elliptical entrance 5 at its outer side for a purpose to be presently described. The bolt 6 has a head 7 and is passed through the hole in one fish-plate and also through the hole in the rail. The threaded end of the bolt then projects through the hole 4 in the other fish-plate. A collar 8 has a central circular opening 9, through which the threaded end of the bolt projects, and at the inner side and surrounding the circular opening said collar is provided with an elliptical flange 10, which projects laterally toward the fish-plate. This elliptical flange 10 is of a size and shape to correspond with the shape of

the entrance 5 to the hole 4 in the fish-plate, so that the flange may enter said entrance, but be prevented from turning therein. It is obvious that the shape of the flange and the entrance to the hole 4 in the fish-plate may be varied so long as it is other than circular, the object being to prevent the collar from turning. The outer circumferential edge of the collar is provided with a plurality of depressions 11. The nut 12 may be of any exterior angular shape desired; but each side is provided with a bottom recess or depression 13.

A washer 14, of some suitable flexible metal which will set in any position to which it is bent, has position on the bolt between the recesses of the nut and the recesses in the collar. This washer remains flat during the operation of turning the nut on the threaded end of the bolt, and when the nut has been screwed as far as it can go on the bolt and the flange 10 and collar forced into contact with the fish-plate portions 15 of the washer may then be bent inward, so as to enter the circumferential depressions 11 in the collar, and other portions 16 of the washer may be bent outward into the depressions 13 of the nut, as seen in Fig. 2, so as to lock the nut to the stationary collar and prevent its turning. When it is desired to remove the nut, the bent portions of the metal washer may be flattened out by bending the same away from the recesses and depressions and the nut can then be removed.

Having thus described my invention, what I claim as new, and desire to secure by Letters Patent, is—

In a nut-lock, the combination with the plates to be secured together one of which has a hole with an entrance shaped so as to be other than circular, of a bolt; a perforated collar having a laterally-projecting flange at one side shaped so as to fit said hole-entrance and a plurality of depressions in its opposite side; a nut having recesses, and a flexible metal washer between the collar and nut and engaging the depressions in the collar and the recesses in the nut to lock the two together.

In testimony whereof I affix my signature in presence of two witnesses.

ARTHUR R. KEENE.
